US00D904039S

(12) **United States Design Patent** (10) **Patent No.:** **US D904,039 S**
(45) **Date of Patent:** **** Dec. 8, 2020**

(54) **SHOWER ACCESSORY HANGER**

(71) Applicant: **Water Pik, Inc.**, Fort Collins, CO (US)

(72) Inventor: **Eric Summers**, Fort Collins, CO (US)

(73) Assignee: **WATER PIK, INC.**, Fort Collins, CO (US)

(**) Term: **15 Years**

(21) Appl. No.: **29/625,851**

(22) Filed: **Nov. 13, 2017**

(51) **LOC (12) Cl. 06-06**

(52) **U.S. Cl.**

USPC **D6/301**; D6/309; D6/313; D6/524

(57) **CLAIM**

The ornamental design for a shower accessory hanger, as shown and described.

DESCRIPTION

FIG. 1 is an isometric view of an embodiment of a shower accessory hanger with certain components shown in dashed lines for environment.

FIG. 2 is a top, front isometric view of the shower accessory hanger of FIG. 1.

FIG. 3 is a front elevation view of the shower accessory hanger of FIG. 1.

FIG. 4 is a rear elevation view of the shower accessory hanger of FIG. 1.

FIG. 5 is a left side elevation view of the shower accessory hanger of FIG. 1.

FIG. 6 is a right side elevation view of the shower accessory hanger of FIG. 1.

FIG. 7 is a top plan view of the shower accessory hanger of FIG. 1; and,

FIG. 8 is a bottom plan view of the shower accessory hanger FIG. 1.

The broken lines in the drawings illustrate the environment of the claimed design and form no part thereof.

1 Claim, 4 Drawing Sheets
